ATTORNEY

UNITED STATES PATENT OFFICE.

CHRISTOPHER RIESSNER, OF NEW YORK, N. Y.

PETROLEUM COOKING-STOVE.

SPECIFICATION forming part of Letters Patent No. 258,676, dated May 30, 1882.

Application filed March 11, 1882. (No model.)

To all whom it may concern:

Be it known that I, CHRISTOPHER RIESSNER, of the city, county, and State of New York, have invented certain new and useful 5 Improvements in Petroleum Cooking-Stoves, of which the following is a specification.

This invention has reference to improvements in petroleum and other cooking-stoves, whereby the heating-surface of the stove is considerably enlarged by means of detachable extension-tops, through which the gases of combustion are drawn off to the outside.

In the accompanying drawings, Figure 1 represents a plan; Fig. 2, a front elevation, partly 15 in section, of my improved petroleum cooking-stove. Figs. 3 and 4 are details showing the modes of connection of the extensions with the top part of the stove, and Fig. 5 is a perspective view of the extension-top.

20 Similar letters of reference indicate corresponding parts.

In the drawings, A represents the top part of a petroleum, gas, or other cooking-stove, which is provided with a pot-hole and removable lid. In the side walls of the top part, A, are arranged draft-openings *a* for the passage 25 of the gases of combustion, and also socket-holes *A'*, into which are inserted the hook-shaped locking-catches *B'* of the extension-tops *B*, which are applied to one, two, or more 30 of the side walls of the stove. The extension-tops *B* are made open at that end which is connected by the locking-catches *B'* to the top part of the cooking-stove, the adjoining side 35 walls being closed and the outer end walls provided with draft-openings *b*, as shown clearly in Fig. 5. The hooks *B'* of the extension-top *B* are inserted through the socket-holes *A'* and bind upon the rim or ledge at the under side 40 of the top plate of the stove, said rim or ledge being preferably semicircular in cross-section in the socket-holes *A'*, as shown in Fig. 4, so that when the catches *B'* are inserted into the socket-holes *A'* of the top part, A, the same will 45 securely support the extension-top *B* alongside of top part, A, and on a level therewith, as shown in Fig. 2.

The extension-tops *B* may be attached to one or more sides of the top part, A, so that space for two, three, four, or five cooking-vessels is provided on the stove, according to the 50 number of extension-tops made use of. The gases of combustion pass through the openings *a* of the top part, A, to the interior of extension-tops *B*, the extension-tops forming draft-flues, 55 whereby the heat is drawn to the extreme ends of the extensions, so as to heat up the vessels placed thereon.

When not required for use the extension-tops may be readily detached from the top 60 part of the cooking-stove and stored away. In shipping they are arranged sidewise to the body of the stove and packed up therewith, requiring less space than when locked to the stove. 65

Having thus described my invention, what I claim as new, and wish to secure by Letters Patent, is as follows:

1. In a petroleum or other cooking-stove, a hollow extension-top flue provided at its outer 70 end with a series of openings for the escape of gas, and an open inner end, in combination with a horizontal flue-section integral with the main stove, a semicircular hook attached to the hollow extension flue, and the socket in 75 the top A, by which the two flues are locked together, substantially as described.

2. In a petroleum or other cooking-stove, the top part, A, having a series of draft-openings, *a*, in combination with an extension, detachable flue with an open end adjoining said top part and a series of exit-openings, *b*, in its outer end, and with the locking devices *B' A'*, substantially as described.

In testimony that I claim the foregoing as 85 my invention I have signed my name in presence of two subscribing witnesses.

CHR. RIESSNER.
